UNITED STATES PATENT OFFICE.

JOHN BERNIA, OF DETROIT, MICHIGAN, ASSIGNOR OF ONE-HALF TO CHARLES E. MARKER, OF DETROIT, MICHIGAN.

SCALE.

1,144,685.

Specification of Letters Patent. Patented June 29, 1915.

Application filed January 22, 1915. Serial No. 3,672.

To all whom it may concern:

Be it known that I, JOHN BERNIA, a citizen of the United States, and a resident of Detroit, in the county of Wayne and State 5 of Michigan, have invented a new and Improved Scale, of which the following is a specification.

This invention relates to scales, particularly to devices whereby bags may be held 10 open to allow filling at one point, and may then be weighed and swung to another point at which they may be detached, whereby the number of bags that may be filled and weighed by the users may be greatly increased over that possible in present practice.

The invention consists in the details of construction shown, described and particularly pointed out in the subjoined claims.

In the drawings, Figure 1 is a vertical section through one embodiment of my invention. Fig. 2 is a section looking downwardly from the plane 2—2 of Fig. 1. Fig. 3 is a vertical section through the dial and adjacent parts. Fig. 4 is a fragmentary section on the line 4—4 of Fig. 3. Fig. 5 is a part front elevation of the dial and pointer. Fig. 6 is an enlarged detail showing the connection between the pointer and actuating pinion.

Similar reference characters refer to like parts throughout the several views.

In the embodiment of my invention shown, a base, that may be formed of three or more legs 1, has rising therefrom the post 2, preferably cylindrical throughout its length, which may be threaded into the base at 3 and may be provided with the longitudinal slot 4, the purpose of which will be hereinafter indicated. A bolt 5, passing through

40 the post, supports, by means of a collar 6, a spiral spring 7 from the lower end of which is suspended a bearing block 8 that is slideable vertically on the post but is prevented from turning in respect thereto by a cross-bar 10 that passes through a downwardly extending flange 11 and the slot 4, and may be secured in place by the nut 12. The bearing block may also be provided with an upwardly extending annular flange 16, and 45 may have an annular ball race 17 in its upper surface. Resting on the balls 18 in the race 17 is a table frame that may comprise the inner hub portion 19 from which radiate a series of arms 20, to the outer ends 50 of which is secured the circular angle iron

rim 21. The arms and rim together constitute a support for the wooden boards 22 upon which the lower ends of the bags may be placed. The hub portion 19 may be provided with a downwardly extending annular flange 25 which incloses the outer edge of the bearing block 8, and may also comprise an upwardly extending flange 26 in which may be threaded the lower end of the tubular casing 27. The latter conceals and protects the spring 7 and supports at its upper end a disk 30 and cap 31 between which may be located the annular flange 33 of a member 34, preferably tubular, that extends upwardly on the post. Balls 35 are interposed 60 in races between the flange 33 and each of the members 30 and 31 to allow free rotation of the casing 27 in respect to the member 34.

In bagging grain or the like, some means 75 is necessary to hold the bags open to allow the material to be shoveled or otherwise delivered thereto. The cap 31 may be provided with the spaced ears 37, each pair of which may be joined by a pivot 38 upon 80 which is mounted to swing vertically a bag-holding device, the body of which is formed of a single piece of strap iron bent to form the cross-piece 39, the arcs 40 and the inwardly extending parallel ends 41 through 85 which the pivots 38 pass. Pins 43 may join the ears 37 at points between the pivots 38 and the cap, and prevent the bag-holding device from falling below a substantially horizontal plane, and hooks 44 may be 90 formed in the lower edges of the bag holders if desired.

Some means is also necessary to prevent the bags from turning about the post as an axis while they are being filled, and for that purpose the cross bar 10 is extended to a point near the edge of the table 20—21—22 and may be perforated to receive the vertical locking bolt 45 that may be received 95 in any one of a series of notches 46, the number of which corresponds to the number of bag holders. A spring 47, that rests on the cross-bar 10 and engages with a collar 48 on the locking bolt, urges the latter upwardly; and the foot lever 50, pivoted to the cross-bar at 51 and joined to the locking bolt by a pin-and-slot connection 52, affords a means whereby the table may be conveniently released to allow rotation about the post.

The tubular member 34, being carried by the casing 27, is, of course, slideable vertically in respect to the post, the amount of the movement being limited by a screw 55 that projects from the post and passes through the longitudinal slot 56 formed in the member 34. Rigidly connected to the last mentioned member, for example, by the screws 57, is a plate 58 provided with rack 10 teeth 59 that mesh with a toothed pinion 60, rotatably mounted on a pin 61, the latter of which projects through the slot 56 and may be screwed into the post 2. The screw 61 is continued outwardly somewhat beyond the face of the pinion and is itself threaded to receive a screw 63 (Fig. 3) by means of which a pointer 64 may be secured thereon. Various connections may be devised for transmitting rotary motion from 15 the pinion to the pointer, but it is preferred to slot the face of the hub, as indicated in Fig. 6, and to rigidly secure to the pointer a tenon 66 that is received in the slot.

Secured upon a shoulder 70 formed upon 25 the upper end of the post, preferably by the nut 71, is a cylindrical casing 72, the rear wall 73 of which may be of metal, the front end being closed by the glass plate 74 and having inset therefrom the dial 75 over 30 which the pointer sweeps to indicate spring deflections, as shown in Fig. 5.

Operation: An operator stationed on one side of the table attaches the empty bags to the bag-holders in an obvious manner. The 35 foot lever is then depressed and the table swung about the post to a point where the filling operation is to take place, whereupon it is automatically locked in position by the bolt 45. The filling operation is then accomplished by another workman—either by shoveling or by manipulating a chute or other conveyer (not shown). When no weight is 40 on the table, the spring 7 holds the lower wall of the slot 56 in engagement with the pin 55 and the pointer then indicates zero; and at the end of the filling operation the weight may be read directly from the dial. The foot lever may then again be depressed and the table swung around to a point at 45 which the filled bag may be removed, and another open bag be simultaneously presented in position to be filled.

It is clear that many changes may be made in the details of my construction without departing from the spirit of my invention. I do not, therefore, wish to be limited otherwise than as indicated by the subjoined claims.

I claim:—

60. 1. A weighing device comprising a base, a post rising vertically therefrom, a spiral spring surrounding the post, a bearing block supported by the spring and slideable vertically on the post, means for preventing the bearing block from turning about the post

as an axis, a table mounted on the bearing block and rotatable about the post, a tubular member rising from the table, said member being arranged to inclose and protect the spring, means carried by the post for indicating the weight of loads on the table, and means carried by the tubular member for actuating the indicating means. 70

2. A weighing device comprising a base, a post rising vertically therefrom, a spiral 75 spring surrounding the post, a bearing block supported by the spring and slideable vertically on the post, means for preventing the bearing block from turning about the post as an axis, a table mounted on the bearing 80 block and rotatable about the post, a tubular member rising from the table, said member being arranged to inclose and protect the spring, means carried by the post for indicating the weight of loads on the table, 85 means carried by the tubular member, and in respect to which the tubular member is rotatable, for actuating the indicating means, and means for preventing rotation of the actuating means about the post as an 90 axis.

3. A weighing device comprising a base, a post rising vertically therefrom, a spiral spring surrounding the post, a bearing block supported by the spring and slideable vertically on the post, means for preventing the bearing block from turning about the post as an axis, a table mounted on the bearing block and rotatable about the post, a tubular member rising from the table, said member 95 being arranged to inclose and protect the spring, means, including a pinion carried by the post, for indicating the weight of articles on the table, a member movable vertically in respect to the post, said last mentioned member being supported on the tubular member and the latter being rotatable in respect thereto, means for preventing the movable member from rotating about the post, a rack carried by the vertically movable member and meshing with the pinion for causing the indicating means to indicate deflections of the spiral spring caused by 100 loads placed on the table. 110

4. A weighing device comprising a base, a post rising vertically therefrom, a spiral spring surrounding the post, a bearing block supported by the spring and slideable vertically on the post, means for preventing the bearing block from turning about the post as an axis, a table mounted on the bearing block and rotatable about the post, a tubular member rising from the table, said member being arranged to inclose and protect the 115 spring, a series of bag holders supported by the tubular member, means carried by the post for indicating the weight of bags on the table, and means carried by the tubular member for actuating the indicating means. 120

5. A weighing device comprising a base, 125

- 5 a post rising vertically therefrom, a spiral spring surrounding the post, a bearing block supported by the spring and slideable vertically on the post, means for preventing the bearing block from turning about the post as an axis, a table mounted on the bearing block and rotatable about the post, a tubular member rising from the table, said member being arranged to inclose and protect the spring, a series of bag holders supported by the tubular member, means carried by the post for indicating the weight of bags on the table, means carried by the tubular member for actuating the indicating means, and means for locking the table at points in its rotation corresponding in number and location to the individual bag holders of the series.

10 6. A weighing device comprising a base, a post rising vertically therefrom, a spiral spring surrounding the post, a bearing block supported by the spring and slideable vertically on the post, means for preventing the bearing block from turning about the post as an axis, a table mounted on the bearing block and rotatable about the post, a tubular member rising from the table, said member being arranged to inclose and protect the spring, a series of bag holders supported by the tubular member, means carried by the post for indicating the weight of bags on the table, means carried by the tubular member for actuating the indicating means, means for automatically locking the table at points in its rotation corresponding in number and location to the individual bag holders of the series, and manually operated means for releasing the table to allow rotation at will.

15 7. A weighing device comprising a base, a post rising vertically therefrom, a spiral spring surrounding the post, a bearing block supported by the spring, said post having a longitudinal slot therein, a cross bar passing through the slot for preventing angular movement of the bearing block about the post, a table mounted on the bearing block and rotatable about the post, a member rising from the table, means carried by the post for indicating the weight of articles on the table, and means carried by the member for actuating the indicating means.

20 8. A weighing device comprising a base, a post rising vertically therefrom, a spiral spring surrounding the post, a bearing block supported by the spring, said post having a longitudinal slot therein, a cross bar passing through the slot for preventing angular movement of the bearing block about the post, a table mounted on the bearing block and rotatable about the post, a member rising from the table, means carried by the post for indicating the weight of articles on the table, and means carried by the member for actuating the indicating means.

25 9. A weighing device comprising a base, a post rising vertically therefrom, a spiral spring surrounding the post, a bearing block supported by the spring, said post having a longitudinal slot therein, a cross bar passing through the slot for preventing angular movement of the bearing block about the post, a table mounted on the bearing block and rotatable about the post, a member rising from the table, means carried by the post for indicating the weight of articles on the table, and means carried by the member for actuating the indicating means, a series of bag holders supported by the member, and means for locking the table at points in its angular rotation corresponding in number and location to the individual bag holders of the series.

30 10. A weighing device comprising a base, a post rising vertically therefrom, a spiral spring surrounding the post, a bearing block supported by the spring, means for preventing angular movement of the block about the post, a table mounted on the bearing block and rotatable about the post, anti-friction members interposed between the block and table, said table including an annular flange that surrounds the edge of the bearing block, a member rising from the table, means carried by the post for indicating the weight of articles on the table, and means carried by the member for actuating the indicating means.

35 11. A weighing device comprising a base, a post rising vertically therefrom, a spiral spring surrounding the post, a bearing block supported by the spring and slideable vertically on the post, means for preventing the bearing block from turning about the post as an axis, a table mounted on the bearing block and rotatable about the post, a member rising from the table, means carried by the post for indicating the weight of loads on the table, means carried by the member for actuating the indicating means, a series of pivots carried by the member, a series of bag holders swingable vertically on the pivots, and means for preventing the bag holders from swinging downwardly about the pivots beyond a predetermined plane.

40 12. A weighing device comprising a base, a post rising vertically therefrom, a spiral spring surrounding the post, a bearing block supported by the spring and slideable vertically on the post, means for preventing the bearing block from turning about the post as an axis, a table mounted on the bearing block and rotatable about the post, a tubu-

- lar member rising from the table, said member being arranged to inclose and protect the spring, means carried by the post for indicating the weight of loads on the table, a pair of spaced plates carried by the tubular member, a member slidable vertically in respect to the post and having an annular flange interposed between the spaced plates whereby the upper end of the tubular member is steadied and the table is prevented from tipping on the bearing block, and means carried by the member with the annular flange for actuating the indicating means.
15. 13. A weighing device comprising a base, a post rising vertically therefrom, a spiral spring surrounding the post, a bearing block supported by the spring and slidable vertically on the post, means for preventing the bearing block from turning about the post as an axis, a table mounted on the bearing block and rotatable about the post, a tubular member rising from the table and rigidly secured thereto, said member being arranged to inclose and protect the spring, a bearing for the upper end of the tubular
- 20
- 25

member whereby it is steadied and the table is prevented from tipping, means carried by the post for indicating the weight of loads on the table, and means supported on the ^{sc} tubular member for actuating the indicating means.

14. A weighing device comprising a base, a post rising therefrom, a spiral spring surrounding the post, a bearing block supported by the spring and slidable vertically on the post, means for preventing the bearing block from turning about the post as an axis, a table mounted on the bearing block and rotatable about the post, a member rising from the table, means carried by the post for indicating the weight of loads on the table, and means carried by the member for actuating the indicating means.

In testimony whereof I sign this specification in the presence of two subscribing witnesses.

JOHN BERNIA.
